ASSIGNORS TO UNITED SHOE MACHINERY CORPORATION, OF PATERSON, NEW
JERSEY, A CORPORATION OF NEW JERSEY.

TOP-LIFT-TRIMMING MACHINE.

Application filed August 25, 1927, Serial No. 215,478, and in Great Britain September 30, 1926.

This invention relates to trimming machines and is herein illustrated as embodied in a machine designed with regard particularly to trimming the top lifts of heels that have been previously developed to final shape. In the manufacture of women's shoes provided with wood heels, for example, it is the practice to shape the heels and cover them before attaching the top lifts. Then, after attaching the top lifts, which are initially oversize, it is necessary to trim them to conform them to the heels with regard not only to their contours but also with regard to their profiles. One of the problems always present in such trimming is to trim the top lift flush with the cover of the heel without marring the cover. Stated generally, an object of the invention is to provide an improved machine for doing this kind of trimming.

Good shoemaking practice also requires slightly beveling of the edge of the top lift at the tread surface to remove the sharp edge and to improve the appearance of the heel, and although top lifts are graded according to their thickness those attached to one lot of heels, while of uniform thickness, are usually thinner or thicker than those attached to another lot of heels. Thus, when, as formerly, a single cutter is used to do both the trimming and the beveling simultaneously, such a cutter is suitable only for a certain thickness of top lift, and if it is used on thinner top lifts and set to produce the necessary bevel it will overlap the heel cover. Then, if it is attempted to produce flush trimming, the overlapping portion of the cutter will cut into or scrape the heel cover. On the other hand, if such a cutter is used to trim a relatively thick top lift, it will produce too much bevel and thus spoil the appearance of the heel.

In view of the problems above stated, the invention provides improved means for trimming and simultaneously beveling top lifts of various thicknesses, to the end that uniformity of the bevel and flush trimming may both be accomplished without marring the covers of the heels.

To accomplish the above-mentioned objects a feature of the invention consists in a novel combination comprising a rotary edge-trim-

ming cutter for trimming the contour of a top lift attached to a heel, a tread-rest and a beveling cutter, said combination being organized to provide two relatively adjustable groups or units of which one includes the contour cutter, while the other includes the tread-rest and the beveling cutter. These two groups or units, moreover, are so related that the meeting faces of the heel and top lift may be located in the plane of one end of the contour cutter by contact of the tread face of the top lift with the tread-rest. Thus, by relatively adjusting the two said groups in accordance with the thickness of the top lifts, the contour cutter may be prevented from lapping and possibly scraping or cutting the heel cover, but since adjustment of the kind referred to does not change the relation between the beveling cutter and the tread-rest, uniform beveling is assured irrespective of adjustments made because of the thickness of the top lifts.

While trimming the sides and back of a top lift, it is desirable to utilize a heel-support, not only to relieve the operator from the necessity for sustaining the heel against the stress applied by the cutters, but also to maintain the top lift in a substantially uniform relation to the cutters, since this operation requires turning the heel while the cutters are operating. On the other hand, when trimming the breast of the top lift, it is not feasible to use a heel-support since this operation requires moving the heel bodily past the cutter rather than turning it rotatively. To meet these conditions the illustrated machine comprises a heel-support adapted to be shifted quickly to and from an operative position so that with one handling of a heel said support may be utilized while trimming around the sides and back of the top lift but may be removed from its operative position to avoid obstructing the work while the breast of the top lift is being trimmed.

In many heels of the type above referred to, for example Louis heels, the pitch or slant of the profile adjacent to the top lift is not the same at the breast as around the back and sides. Usually the profile of the breast is very nearly, if not quite, at right angles to the plane of the tread surface, while around

the sides and back it may have a considerable pitch or slant due to the flaring formation of the heel body adjacent to the top lift. Consequently, the operation of trimming the top lift to conform to the heel body where the two elements meet involves not only the matter of contour, but also the problem of conforming the profile of the top lift to that of the heel body, to the end that the breast as well as the sides and back of the top lift will merge smoothly into the heel body and form, in effect, a continuation of the latter without any perceptible break or change of pitch at the meeting plane.

Accordingly, with regard to the latter consideration, an object of the invention is to provide for utilizing the movements of the heel-support to and from its operative position to effect the desired change of pitch of the profile of the trimmed top lift.

To this end a feature of the invention consists in means arranged to communicate shifting movement of the heel-support to the tread-rest in such a way as to shift the latter back and forth from one to the other of two operative positions angularly related to each other. The illustrated means for this purpose is designed to coordinate the movements of the tread-rest and the heel-support so that when the latter is in its operative position the angle of the tread-rest will be suitable for trimming the back and sides of the top lift and when the heel-support is displaced from its operative position, as described, the angle of the tread-rest will be suitable for trimming the breast of the top lift. Thus, while the heel support is utilized as an actuator to shift the tread-rest, it also indicates visually in which of its two angularly related positions the tread-rest stands.

Referring to the drawings,

Fig. 1 is a front elevation of a toplift trimming machine embodying the invention, the heel-support and the trimming gage being adjusted for trimming the sides and back of a toplift;

Fig. 2 is a top plan view of the forward portion of said machine;

Fig. 3 is a vertical section through the structure intersected by line III—III of Fig. 1 and includes a portion of a Louis heel in working position;

Fig. 4 is a right side elevation of said machine;

Fig. 5 is a horizontal section through the trimming cutters and shows a Louis heel in working position; and

Fig. 6 is a vertical section through the structure intersected by line VI—VI of Fig. 5.

Referring now to Fig. 4, the frame 10 of the illustrated toplift trimming machine is formed with a base 12 adapted to be bolted or otherwise secured to the upper end of a column (not shown). The frame is provided

with bearings for a cutter shaft 14, one of said bearings being indicated at 16. The shaft 14 is provided with a pulley 18 for a belt by which the shaft will be driven in the direction indicated by an arrow in Fig. 4. A cutter 20 for trimming the contour of a toplift is provided with a series of cutting teeth preferably skewed or inclined relatively to the axis of rotation, as represented in Fig. 4, the pitch or inclination of said teeth being preferably such as to cut from the attaching face of the toplift toward the tread face thereof, since the flesh side of a leather toplift is always placed against the body of the heel, and it is desirable to cut from the flesh face toward the grain face of the toplift to remove the fuzz that would otherwise be formed at the flesh face by the cutting teeth. The cutter 20 is affixed to the shaft 14 in well-known manner (Fig. 5) by a longitudinally split and expandable sleeve 22 fitted to a tapering portion 24 of the shaft. A supplemental cutter 26 is arranged in coaxial relation to the cutter 20 and is provided with inclined cutting teeth which project between the teeth of the cutter 20 and are shaped to bevel the edge of the tread surface of the toplift. This beveling cutter, although supported and driven by the shaft 14 is adjustably mounted so that it may be shifted lengthwise of its axis relatively to the cutter 20, as may be desired to regulate the depth of the beveling cut, or as may be required to maintain a uniform bevel for toplifts of different thicknesses. Accordingly, in the construction shown by Fig. 5, the beveling cutter 26 is affixed by a set-screw 28 to a sleeve 30, and the latter is bored to fit a cylindric portion of the shaft 14 and is adapted to slide relatively to the shaft. The rear end of the sleeve 30 is formed with a diametrical groove 32 to receive the ends of a driving pin 34 which extends through the shaft and is secured to the latter by being tightly driven into a transverse hole bored in the shaft. This is a form of spline connection which causes the sleeve to rotate with the shaft but permits the sleeve to be adjusted axially. A circumferential groove formed in the sleeve 30 is occupied by a fork or shipper 36 formed with a cylindric stem 38. (See Fig. 6.) The stem is journaled in an arm of a bell-crank lever 40 provided for the purpose of adjusting the cutter 26. A tension spring 42 (Fig. 5) is attached at its forward end to the lever 40 and at its rear end to the frame 10, and its effect is to retract the cutter 26 from the front of the cutter 20 and thereby maintain the lever 40 against an adjusting screw 44. A stop 46 (Fig. 6) is provided to limit the adjusting movement of the cutter 26 toward the front, this stop being affixed to the frame 10 and arranged to project therefrom toward the front of the machine. The stop 46 extends through a notch in a lug 48 formed on

the lever 40 and is provided with a head at its forward end to arrest the lug 48.

Fig. 5 illustrates a type of Louis heel 50 which embodies a flaring formation around the sides and back adjacent to the toplift 52. The breast 54 of this type of heel, while not exactly at right angles to the plane of the tread face 56 of the toplift, is nevertheless more nearly at right angles thereto than is the profile around the sides and back adjacent to the toplift. Therefore, to continue the profile of the heel body 50 into the toplift it is necessary to maintain the tread face 56 in one plane while trimming around the back and sides, and in another plane angularly related to the first said plane while trimming the breast. The angular relation of these two planes for a heel of the style shown is indicated in Fig. 5 by broken lines *a* and *b*. It will be observed that the relation between the line *b* and the profile of the cutter 20 is more nearly right-angular, whereas the relation between the line *a* and the profile of said cutter is more acute. To provide for this change of angular relation the machine is provided with a tread-rest 60 which may be readily and quickly shifted back and forth from one to the other of two angularly related operative positions corresponding to the lines *a* and *b*.

The tread-rest is essentially a flat plate, and stands vertically. It is provided near the top and bottom with arms 62 (Fig. 4) through which a vertical pivot pin 64 extends to connect the tread rest with an adjustable support 66. This support is formed with a cylindric shank or stem 68 arranged to slide horizontally in a bearing 70 formed in the frame 10. A key 72 (Figs. 1 and 4) and groove 74 form a spline connection to prevent turning movement of the stem about its axis. The bearing 70 is preferably split at its under side and is provided with a bolt 76 by which it may be contracted to clamp the stem 68. For the purpose of adjusting the tread rest along lines parallel to the axis of the cutters and in accordance with the thickness of the toplifts, the stem 68 is provided with a notch 78 into which a tooth or pin 80 projects from a rock shaft 82. The rock shaft is journaled in the frame 10 and is provided with an operating handle 84.

The pivot pin 64, in addition to connecting the tread-rest and the support 66, extends also through the bell crank lever 40 which is carried by said support. Furthermore, the adjusting screw 44, by which the beveling cutter 26 is adjusted relatively to the cutter 20, is carried by the support 66. Consequently, when the support 66 is adjusted by manipulation of the handle 84 to shift the tread-rest forward or back, the beveling cutter 26 partakes of this adjustment and remains in constant relation to the tread-rest.

The aforesaid angular adjustment of the

tread-rest consists in movement about the axis of the pivot pin 64 and is effected by an arm 86 formed with a cam surface 88 (Fig. 3). The arm 86 is affixed to a rock-shaft 90 journaled in a boss 92 formed on the tread-rest 60 (Fig. 2), and for this purpose the arm is preferably split, as shown in Figs. 1 and 4, and is provided with a bolt 94 by which it may be contracted to grip the rock-shaft tightly. The cam surface 88 is formed at the left-hand end of the arm 86 as viewed in Figs. 1 and 2 and cooperates with an adjustable abutment 96. A tension spring 98 is connected at its forward end to the tread-rest, and at its rear end to the frame 10, its effect being to draw the tread-rest toward the rear and thereby maintain the arm 86 against the abutment 96. The abutment 96 is shown as a screw and is carried by the adjustable support 66. Consequently, since the abutment 96 partakes of adjustments of the support 66, these adjustments do not affect the angular adjustment of the tread-rest. The screw 96 serves to maintain the work-engaging face of the tread-rest in the angular position indicated by broken line *a* in Fig. 5, although this angular position is, of course, subject to variation by adjustment of said screw. When the arm 86 is in the position shown, its left-hand end is supported by a lug 100 (Fig. 3) formed on the tread-rest.

When it is desired to shift the tread-rest from the position indicated by broken line *a* (Fig. 5) to that represented by broken line *b*, the rock-shaft 90 is turned in a clockwise direction to disengage the arm 86 from the abutment 96. This disengagement enables the spring 98 to draw the tread-rest to the rear by swinging it slightly about the axis of the pivot pin 64. The extent of angular movement of the tread-rest is controlled by a second abutment shown as a screw 102. This screw is also carried by the support 66 and is arranged to engage a portion 104 (Fig. 1) of the arm 86, which portion is preferably semi-circular to maintain its abutting contact with the screw 102 when the arm 86 is turned clockwise approximately 180° from the position shown. This turning movement of the arm 86 is arrested by a lug 106 projecting from the tread-rest and arranged to be engaged by a pin 108 carried by the arm. With this construction the tread-rest may be shifted back and forth from one to the other of its two angularly related operative positions each of which is variable independently of the other.

The machine is also preferably provided with a heel support to sustain the heel against the cutting stresses. In the illustrated machine the support for this purpose comprises an arm 112 and a heel-engaging roll 110 carried thereby. This support is useful in trimming around the sides and back of a toplift, since such trimming is executed progres-

sively by rotative movement of the heel. On the other hand, when trimming the breast of the toplift it is necessary to move the heel bodily rather than rotatively, and accordingly it is desirable to provide for removing the roll 110 from its operative position when the machine is to be used to trim the breast of the toplift. Accordingly, the heel-support is cooperatively related to the tread-rest in such manner as to utilize the movements of the support to and from its operative position to effect the aforesaid shifting of the tread-rest back and forth from one to the other of its two angularly related working positions. To this end, the arm 112 which carries the roll 110 is rigidly related to the arm 86 through a connection afforded by the rock-shaft 90, said rock-shaft being, in fact, an integral part of the arm 112. The split construction 20 of the arm 86 and the clamping bolt 94 provide for relative angular adjustment of the arms 86 and 112 so that the roll 110 may be adjusted to stand at any desired level when the arm 86 is supported by the lug 100, as shown in Fig. 3. This lug, therefore, sustains the heel support in its operative position.

Provision is also made for adjusting the roll 110 lengthwise of the arm 112, the latter being provided with a radial slot 114 for this purpose. The roll 110 may rotate relatively to a screw 116 by which it is connected to the arm 112, said screw being arranged to extend through the slot 114 and through two cooperative clamping plates 118 which are mortised in the slot. The plate 118 that lies against the rear face of the arm 112 is provided with an internal screw-thread to engage the thread of the screw 116, but the plate that lies between the arm 112 and the roll 110 is adapted to slide relatively to the screw. Consequently, when the screw is tightened it causes the plates 118 to clamp the arm 112 between them, a bushing being arranged in the roll 110 to prevent the clamping pressure from being applied to the roll.

To control the depth of trimming so that the trimmed contour of the toplift will be flush with the heel body 50, the machine is provided with a trimming gage 120 which, as shown by Fig. 5, is close to the front face of the cutter 20 and arranged to engage the heel body. This gage is preferably provided with a semi-circular edge 122 to be used when trimming around the sides and back of a toplift and when trimming a concave breast. It is also provided with a straight edge 124 to be used when trimming a straight breast.

The trimming gage 120 is connected to a supporting bracket 126 by a pivot member 128 which provides for turning the gage 180° to place the edges 122 and 124 alternatively in working position. The bracket 126 is provided with a retaining latch 130 which enters two diametrically opposite notches 132 formed in the gage to lock the latter in its

two working positions. The latch 130 is pivotally connected to the bracket 126 by a pin 134 and is normally held in engagement with the gage by a compression spring 136.

The supporting bracket 126 is provided with a cylindric shank or stem 138, and the frame 10 is provided with a bore to receive said stem (see Figs. 1 and 2). An adjusting screw 140 is screwed into the frame and is arranged to engage the rear end of the stem 138 to adjust the gage 120 forward and back, as may be necessary to provide clearance between the gage and the cutter 20. The bracket 126 is normally drawn to the rear and held in engagement with the adjusting screw 140 by a tension spring 142 (Fig. 2).

Provision is also made for adjusting the bracket 126 about the axis of its stem 138 for the purpose of adjusting the trimming gage transversely of the axis of the trimming cutters, so that a toplift may be trimmed flush with the body of a heel of any shape or size. For this purpose the bracket 126 is provided with a lug 144 arranged to be engaged by the lower end of an adjusting screw 146 screwed into the frame. The tension spring 142 is connected to the bracket 126 in such relation as to maintain a rotational tendency of the bracket 126 to turn about the axis of the stem 138, the lug 144 being thereby maintained against the adjusting screw 146. The spring 142 thus does double duty in that it maintains one portion of the bracket against the adjusting screw 146 and another portion of said bracket against the adjusting screw 140, at the same time permitting these adjusting screws to effect the two described adjustments independently of each other.

Assuming that the machine is about to be used to trim the toplift of a heel, and that all the necessary adjustments have been made, the operator may begin by first trimming the toplift flush with the sides and back of the heel body. For this part of the operation the supporting roll 110 and the trimming gage 120 will occupy the positions shown in Fig. 1. The machine is capable of operating either on an unattached heel or on a heel that has been attached to a shoe as represented in Fig. 5. As the heel is rotated in contact with the supporting roll 110 and the edge 122 of the trimming gage, the operator will maintain the tread face 56 of the toplift in contact with the tread-rest 60 to control the pitch of the profile generated by the trimming cutter 20. At this time the work-engaging surface of the tread-rest 60 will stand in the position indicated by broken line *a* in Fig. 5. While the cutter 20 is operating to trim the back and sides of the toplift flush with the body of the heel, the supplemental cutter 26 operates to bevel the tread surface as indicated at 57. Having trimmed around the sides and back of the toplift, the operator will proceed to trim the breast, but before doing so he will

- swing the supporting roll 110 upwardly and to the right to remove it from the field of operation so that the heel may be moved bodily up or down without encountering said roll.
- 5 The act of swinging the supporting roll 110 away from its operative position results in changing the angle of the tread-rest from the position indicated by the broken line *a* to that indicated by the broken line *b* in Fig. 5,
- 10 the latter position being the one better suited to the requirements of breast-trimming. If, now, the breast of the heel is concave, as represented in Fig. 1, the trimming gage 120 will be left in the position shown, to enable the
- 15 cutters to enter the concavity as the heel is moved up or down. On the other hand, if the breast of the heel is straight, the operator will turn the gage 180° about its pivot 128 to place the straight edge 124 in operative position.
- 20 In either case the trimming of the breast will then be accomplished by moving the heel up or down in contact with the right-hand edge of the gage, the cutters 20 and 26 now being effective to trim and bevel the breast of the
- 25 toplift.

Since the tread-rest 60 and the supporting roll 110 are in their respective breast-trimming positions in consequence of the procedure above described, the order of procedure for the next heel may be the reverse of that described, to avoid making unnecessary changes in their positions. Thus, the trimming of the next toplift will preferably be begun by first trimming and beveling the

30 breast, and when this step has been accomplished the supporting roll 110 may be returned to the position shown. By returning the supporting roll 110 to its operative position, the arm 86 will be caused to re-engage

35 the screw 96, and the cam surface 88 will cooperate with said screw to shift the tread-rest from the position indicated by broken line *b* to that indicated by broken line *a* in Fig. 5. The machine is thus restored to the desired

40 condition for trimming and beveling the sides and back of the toplift.

Although the support 66 is adjustable to locate the edges of the meeting faces of the heel body and the toplift in the plane of the

45 front face of the cutter, adjustments for this purpose do not affect the angular adjustments of the tread-rest or the depth of the beveling cut, since the adjusting screws 96 and 102 as well as the bell-crank lever 40 and its adjusting screw 44 are all carried by said support. Consequently, when the support 66 is adjusted with regard to the thickness of a lot of toplifts, or even a single toplift, the

50 screws 96 and 102 and the beveling cutter

55 will partake of such adjustment and maintain their respective individual adjustments previously made.

Having described our invention, what we claim as new and desire to secure by Letters

60 Patent of the United States is:—

1. A top-lift-trimming machine comprising two relatively adjustable units one of which includes a rotary cutter arranged to trim the contour of a top lift attached to a heel, and the other of which includes a tread-rest for the top lift and a cutter arranged to bevel the edge of the tread face of the top lift, said units being relatively adjustable to locate the edge of the attaching face of the top lift and one end of said contour cutter in substantially flush relation.

2. A top-lift-trimming machine comprising a rotary cutter arranged to trim a top lift attached to a heel, a tread-rest adjustable to locate the edge of the attaching face of the top lift in the plane of one end of said cutter, and a cutter arranged to bevel the tread of the top lift, said beveling cutter being adjustable relatively to the first said cutter and being connected to said tread-rest to partake of adjusting movement of the latter.

3. A top-lift-trimming machine comprising a rotary cutter arranged to trim a top lift attached to a heel, a tread-rest, means for adjusting said tread-rest lengthwise of the axis of said cutter to locate the edge of the attaching face of the top lift in flush relation to one end of said cutter, and a cutter arranged to bevel the tread of the top lift, said beveling cutter being also arranged to partake of such adjustment of said tread-rest and being adjustable relatively to said tread-rest to regulate the depth of the beveling cut.

4. A top-lift-trimming machine comprising two relatively adjustable units one of which includes a rotary cutter arranged to trim the contour of a top lift attached to a heel, and the other of which includes a tread-rest for the top lift and a rotary cutter arranged to bevel the tread of the top lift, said cutters being coaxial and said units being relatively adjustable to insure clearance of said contour cutter by the heel while the contour cutter is trimming the top lift flush with the heel.

5. A top-lift-trimming machine comprising a rotary cutter shaft, a contour cutter affixed thereto, a beveling cutter supported by said shaft and having a spline connection therewith, a tread-rest arranged to position the top lift of a heel so that said cutters may operate simultaneously on the top lift, one to trim the contour and the other to bevel the tread, said tread-rest being adjustable to locate the edge of the attaching face of the top lift in flush relation to one end of said contour cutter, and means arranged to communicate such adjusting of the tread-rest to said beveling cutter.

6. A top-lift-trimming machine comprising an adjustable support, a tread-rest carried thereby, a rotary cutter arranged to bevel the tread of the top lift of a heel held against said tread-rest, and a rotary cutter arranged to trim the contour of such top lift

while said beveling cutter is operating, said support being adjustable to locate the edge of the attaching face of the top lift in flush relation to one end of said contour cutter, and said beveling cutter being connected to said support to partake of such adjustment.

5 7. A top-lift-trimming machine comprising a rotary cutter arranged to trim the contour of a top lift attached to a heel, a tread-rest, an adjustable support by which said tread-rest is carried to locate the edge of the attaching face of the top lift in the plane of one end of said cutter, a cutter arranged to bevel the tread surface of the top lift, and 10 adjustable means connecting said support and said beveling cutter to communicate adjusting movement of said support to the beveling cutter and to adjust the latter relatively to said support.

15 8. A top-lift-trimming machine comprising two coaxial trimming cutters having interjacent cutting teeth, one of said cutters being arranged to trim the contour of and the other being formed to bevel a top lift 20 attached to a heel, and a tread-rest adjustable relatively to said contour cutter in accordance with the thickness of the top lift, said beveling cutter being axially adjustable relatively to said contour cutter and being connected to said tread-rest to be adjusted by adjusting the latter as aforesaid.

25 9. A top-lift-trimming machine comprising a rotary cutter arranged to trim the contour of a top lift attached to a heel, a trimming gage arranged in confronting relation to one end of said cutter to engage the perimeter of the heel, a tread-rest arranged to locate the edge of the attaching face of the top lift in flush relation to said end of said cutter, and a rotary cutter adjustable relatively 30 to said contour cutter and arranged to bevel the tread of the top lift while said contour cutter is operating.

40 10. A top-lift-trimming machine comprising two relatively adjustable trimming cutters arranged to rotate about a common axis to operate simultaneously on a top lift attached to a heel, one to trim the contour of such top lift and the other to bevel the tread thereof, and a tread-rest adjustable according to the thickness of the top lift to locate the edge of the attaching face of the top lift in the plane of one end of said contour cutter, said beveling cutter being connected to 45 said tread-rest to partake of such adjustment of the latter and thereby maintain uniformity of the beveling cut for top lifts of different thicknesses.

55 11. A top-lift-trimming machine comprising a rotary cutter arranged to trim the contour of a top lift attached to a heel, and a trimming gage arranged in confronting relation to one end of said cutter to engage the 60 perimeter of the heel, said gage having a

curved heel-engaging edge and a straight 65 heel-engaging edge and being adjustable to place said edges alternatively in work-engaging position.

70 12. A top-lift-trimming machine comprising a rotary cutter arranged to trim the contour of a top lift attached to a heel, and a trimming gage arranged in confronting relation to one end of said cutter to engage the perimeter of the heel, said gage being adjustable about an axis approximately concentric to the axis of said cutter and having both a curved heel-engaging edge and a straight heel-engaging edge arranged to be brought alternatively to heel-engaging position by such adjustment, and means arranged 75 to lock said gage when either of said edges is in operative position.

80 13. A top-lift-trimming machine comprising a rotary cutter arranged to trim the contour of a top lift attached to a heel, and a trimming gage arranged in confronting relation to one end of said cutter to engage the perimeter of the heel, said gage having dissimilar heel-engaging edges and being adjustable about an axis to place said edges alternatively in operative position, said gage being otherwise adjustable to regulate the depth of the trimming cut.

85 14. A top-lift-trimming machine comprising a rotary cutter arranged to trim the contour of a top lift attached to a heel, a trimming gage arranged in confronting relation to one end of said cutter to engage the perimeter of the heel, and a support for said gage adjustable to regulate the depth of the trimming cut, said gage having dissimilarly shaped heel-engaging edges and being adjustable relatively to said support to place said edges alternatively in operative position.

90 15. A top-lift-trimming machine comprising means arranged to trim a top lift attached to a heel, an angularly adjustable tread-rest, a movable heel-support, and means arranged to translate movement of said heel-support into angular adjustment of 100 said tread-rest.

105 16. A top-lift trimming machine comprising means arranged to trim a top lift attached to a heel, an angularly adjustable tread-rest, a heel-support movable to and from an operative position, and means operable by said heel-support to shift said tread-rest back and forth from one to the other of two operative positions angularly related to each other.

115 17. A top-lift-trimming machine comprising means arranged to trim a top lift attached to a heel, an adjustable support, an adjustable tread-rest carried by said support, a heel-engaging member carried by said support to sustain the heel against the trimming stresses, said member being movable relatively to said support, and means operable by said member to adjust said tread-rest.

back and forth from one to the other of two operative positions.

18. A top-lift trimming machine comprising means arranged to trim a top lift attached to a heel, an adjustable support, an angularly adjustable tread-rest carried by said support, means arranged to shift said tread-rest back and forth from one to the other of two operative positions angularly related to each other, and individually adjustable devices carried by said support to establish said operative positions.

19. A top-lift-trimming machine comprising means arranged to trim a top lift attached to a heel, an angularly adjustable tread-rest, a heel-rest movable to and from an operative position, and a cam means operable by movement of said heel-rest to shift said tread-rest back and forth from one to the

other of two operative positions angularly related to each other.

20. A top-lift-trimming machine comprising means arranged to trim a top lift attached to a heel, an adjustable support, a tread-rest and a heel-rest both carried by said support and adjustable relatively thereto, means operated by adjusting movement of said heel-rest to shift said tread-rest back and forth from one to the other of two operative positions angularly related to each other, and means for adjusting said support to locate the top lift so that said trimming means will clear the heel while trimming the top lift flush with the heel.

In testimony whereof we have signed our names to this specification.

JOSEPH GOULDBOURN.

REGINALD BOYD WOODCOCK.
